PNEUMATIC TUBE DISPATCH TERMINAL

Ross Cook, Rolling Hills, Calif., assignor to Ross Cook,
Inc., Los Angeles, Calif., a corporation of California

Filed Apr. 12, 1968, Ser. No. 11,424

Term of patent 14 years

Int. Cl. D23—99; D20—99

U.S. Cl. D23—167

FIG. 1.

FIG. 2.

FIG. 3.

FIG. 4.

FIGURE 1 is a front elevational view of a pneumatic tube terminal incorporating my new design;

FIG. 2 is a top plan view thereof;

FIG. 3 is an end elevational view thereof; and

FIG. 4 is a perspective view thereof.

I claim:

The ornamental design for a pneumatic tube dispatch terminal, substantially as shown and described.
